[57] CLAIM

The ornamental design for a electronic thermometer probe, as shown.

DESCRIPTION

FIG. 1 is a front elevational view of a electronic thermometer probe showing our new design;

FIG. 2 is a left side elevational view;

FIG. 3 is a right side elevational view;

FIG. 4 is a rear elevational view;

FIG. 5 is a top plan view;

FIG. 6 is a bottom plan view; and

FIG. 7 is a cross-sectional view taken along line 7—7 of FIG. 1 thereof.
